UNITED STATES PATENT OFFICE.

WILLIAM T. VAUGHN, OF FORT SMITH, ARKANSAS, ASSIGNOR OF ONE-HALF TO R. C. PETTY, OF BROOKEN, OKLAHOMA.

DESIGN FOR A MANDOLIN.

50,545.

Specification for Design.

Patented Mar. 27, 1917.

Application filed August 21, 1916. Serial No. 116,207. Term of patent 14 years.

To all whom it may concern:

Be it known that I, WILLIAM T. VAUGHN, a citizen of the United States, residing at Fort Smith, in the county of Sebastian and State of Arkansas, have invented a new, original, and ornamental Design for a Mandolin, of which the following is a specification, reference being had to the accompanying drawing, forming part thereof, wherein—

The figure is a perspective view of a mandolin showing my new design.

I claim:

The ornamental design for a mandolin as shown.

WILLIAM T. VAUGHN.
